DETACHABLE SHOE HEEL

Filed April 30, 1928

FIG. 3

UNITED STATES PATENT OFFICE

MANUEL S. GUTIÉRREZ, OF LOS ANGELES, CALIFORNIA, ASSIGNOR OF ONE-HALF TO
JOSEPH D. ZUBIA, OF LOS ANGELES, CALIFORNIA

DETACHABLE SHOE HEEL

Application filed April 30, 1928. Serial No. 274,095.

My invention relates to shoes, boots, and the like, and it has for a purpose the provision of a simple, durable, and effective means for fixedly securing a heel to a shoe in such manner as to permit the ready detaching of the heel, should it become damaged or unduly worn, and the substitution of a new heel.

Further, my invention permits heels of various heights to be used on one and the same shoe, thus permitting the latter to be used as a dress or walking shoe.

I will describe only one form of detachable shoe heel embodying my invention and will then point out the novel features in the claim.

In the accompanying drawing:

Fig. 1 is a view showing in-side elevation and partly in section one form of shoe having applied thereto one form of detachable heel embodying my invention;

Fig. 2 is a view similar to Fig. 1 showing the released position of the parts for holding the heel on the shoe incident to removal of the heel;

Fig. 3 is a vertical sectional view taken on the line 3—3 of Fig. 1;

Fig. 4 is a detail perspective view of the groove member shown in the preceding views;

Fig. 5 is a detail perspective view of the shoe heel with the respective parts of the attaching means applied thereto; and

Figs. 6 and 7 are detail perspective views of certain parts of the attaching means carried by the shoe heel.

Referring specifically to the drawings, my invention in its present embodiment comprises a groove member in the form of an elongated plate 15, of metal or other suitable material, provided at intervals along its length with openings 16 through which nails, rivets, or other suitable fastening members 18 are extended for securing the plate to the under side of the body of the shoe, as clearly illustrated in Fig. 1, the plate being bent to conform to the curvature of the corresponding portions of the shoe. At the rear end of the plate two lips 19 are provided and which lips are arranged in converging relation so

that the intervening space provides a groove of dovetail form, as will be clear from an inspection of Fig. 3. These flanges 19 project from the bottom of the heel portion of the shoe to be engaged by a head member on the heel of the shoe, and the plate 15 is provided with a slot 20 in which a latch lug is adapted to be received.

The heel H of the shoe is provided at its upper side with a pair of spaced channels 60 traversely converging to form an intervening elongated tongue 21 of dovetail form in cross-section as illustrated in Fig. 3. In covering relation to the tongue and fixedly secured to the heel by means of fastening members 22 is a plate 23 preferably of metal, designed to reinforce the tongue and coacting with the groove member to retain the heel on the shoe. By reference to Fig. 3, it will be noted that the plate 23 is of such width as to produce 70 in effect a continuation of the tongue transversely so that the major holding stress is imposed on the plate and not on the tongue which is usually formed of wood.

As shown in Figs. 1 and 2, the tongue 21 is provided with a slot 24 designed to receive a latch lever 25 and its lug 26. One end of the lever is provided with a projection 27 adapted to seat within a socket 28 of the heel in a manner to permit the required pivotal movement of the lever incident to occupying latching and non-latching positions. The latch lever is disposed beneath the plate 23, and the plate is provided with a slot 29 through which the lug 26 can project to engage within the slot 20 of the plate 15. The upper and lower edges of the lug 26 are rounded as shown in Figs. 1 and 2, the lower rounded edge acting as a cam to move the lug to a projected or latching position, such 85 position being positively defined by a shoulder 26a on the lug, which engages the plate 23.

In the body of the heel, below the tongue 21, is a pocket 30 in which is slidably received an actuating plunger 31 yieldably urged to the projected position shown in Fig. 1 by means of a spring 32 disposed within the pocket. The plunger is limited in its longitudinal movement by means of a pin 33 extended through the pocket and through a 100

slot 34 in the plunger. As shown in Fig. 7 the plunger is provided with a recess of a shape to receive the curved lower edge of the latch lug 26 in order that the lug may occupy a retarded or non-latching position incident to the removal of the heel from the shoe.

In practice, the heel is applied to the shoe by presenting the exposed end of the tongue to the rear end of the groove and while 10 pressing the plunger 31 inwardly with the finger moving the heel downwardly on the shoe, thereby causing the tongue to move into the groove until the upper end of the plate 15 abuts the inner ends of the channels forming the tongue 21. In this position of the tongue, the lug 26 is in registration with the slot 20 so that by releasing the plunger 31 the spring 32 acts to reject the plunger and thereby cam the lug upwardly into the slot 20. In 20 this manner the tongue is secured against removal from the groove, and through the co-action of the tongue and groove the heel is secured in fixed position upon the shoe.

To detach the heel, the plunger 31 is forced 25 inwardly as illustrated in Fig. 2 until the lower edge of the lug 26 seats within the recess 35, thereby permitting lowering of the lug and its removal from the slot 20. By moving the heel upwardly, as indicated by the 30 arrow in Fig. 2, the tongue can now be removed from the groove and as a consequence the heel is now detached from the shoe.

It will be understood that heels of various heights can be applied to a single shoe so as to 35 convert the shoe into a walking shoe or a dress shoe, and irrespective of the height of the heel my attaching means will operate to fixedly secure the heel in proper position upon the shoe.

40 Although I have herein shown and described only one form of detachable shoe heel embodying my invention, it is to be understood that various changes and modifications may be made herein without departing from 45 the spirit of the invention and the spirit and scope of the appended claim.

I claim:

Means for detachably securing a heel to a shoe comprising a groove member adapted 50 to be secured to the shoe and including a plate provided with flanges spaced and in converging relation to form an intervening groove of dovetail contour, said plate being provided with a slot at a point between the flanges, a 55 head of dovetail form adapted to be secured to the heel and having a sliding fit within the groove formed by said flanges, said tongue member being provided with a slot, a latch lever adapted to be pivoted within the heel 60 and having a lug adapted to project through the slot of the tongue member and into the slot of the groove member, said lug having a rounded projection, a plunger adapted to be mounted for longitudinal movement with 65 the heel and having a recess to receive said

projection when in one position and in the other position to engage the projection to move the lug into the slot of the groove member for securing the tongue member against removal from the groove member, a pin engaging the plunger to limit longitudinal movement of the latter, and a spring engaging the plunger to yieldably urge the latter to a position in which the projection is disposed in said recess.

Signed at Los Angeles, in the county of Los Angeles and State of California, this 14th day of April, A. D. 1928.

MANUEL S. GUTIÉRREZ.
